UNITED STATES PATENT OFFICE.

RUBY P. STINE, OF ADAMS, INDIANA.

WATER-BED FENCE.

Application filed September 30, 1921. Serial No. 504,361.

To all whom it may concern:

Be it known that I, RUBY P. STINE, a citizen of the United States, residing at Adams, in the county of Decatur and State 5 of Indiana, have invented certain new and useful Improvements in Water-Bed Fences, of which the following is a specification.

This invention relates to improvements in water bed fence, and the prime feature of 10 the invention is the provision of a fence so arranged that water and refuse will readily pass through and over the fence while stock will be prevented from passing the fence.

A further feature of the invention is the 15 provision of abutments so arranged that the fence proper will be fully anchored, while the banks of the stream will be prevented from washing adjacent the fence structure.

A further feature of the invention is the 20 provision of means for adjustably connecting the fence to the abutments so that a fence of prescribed dimensions will fit and properly co-operate with abutments of uneven proportion.

25 A further feature of the invention is the provision of means for reinforcing parts of the fence to prevent yielding thereof due to pressure of water and trash or other foreign particles against the fence structure.

30 Other objects and advantages will be hereinafter more fully set forth and pointed out in the accompanying specification.

In the accompanying drawings,

Figure 1 is a top plan view of the water 35 bed fence structure applied to use,

Figure 2 is a longitudinal sectional view as seen on line 2—2 Figure 1,

Figure 3 is a top plan view of the supporting bar employed for supporting the upper 40 end of the fence structure showing the manner of bracing the same,

Figure 4 is a detail elevation partly in section showing the manner of adjustably supporting the fence structure upon the 45 abutment,

Figure 5 is a detail view showing a modified means for attaching the fence bars to the supporting bar, and

50 Figure 6 is a view showing a supporting means for the fence structure at a point between its ends.

55 Referring to the drawings, 1 and 2 indicate the abutments which are placed along the opposite banks of the stream and parallel therewith, said abutments being preferably constructed of concrete and radiat-

ing from one end of each abutment and extending tangentially thereof are reinforcing wings 3 and 4 respectively, the wings being attached or formed integral with the 60 side faces of the abutments so that flat shoulders 5 and 6 will be formed at the upstream ends of the abutments.

The opposite or down stream ends of the abutments 1 and 2 are provided with ledges 65 7 upon which rests a support 8 for the upper ends of fence forming bars 9, said support being preferably of I-beam formation, and in order to adjustably anchor the ends of the support to the abutments, anchoring 70 plates 10 are rested upon the ledges 7 and are attached thereto in any suitable manner as by means of bolts 11, the headed ends of which are embedded in the abutments, the upper ends of the bolts extending through 75 the ends of the anchoring plates and having nuts 12 for securing the plates thereon. The anchoring plates 10 are each provided with a longitudinal slot 13 through which extend clamping bolts 14, the threaded ends 80 of the bolts 14 being introduced through the slots 13 before the plates are secured to the abutments, the length of said bolts 14 being such that they will extend a distance above the upper edge of the support 8 and project through a plate 15 which passes over the top of the support 8, nuts 16 being employed for clamping the plate 15 against the support 8. The bars 9 are preferably 85 substantially A-shape in cross section and have their upper ends secured to one edge of the support 8 by means of bolts 17, or the like, while the lower ends of the bars 9 are attached to a cross bar 18, said cross bar being preferably angular in cross section 90 and of such a length as to have its ends extend over and engage the shoulders 5 and 6 of the abutments 1 and 2, consequently a major portion of the strain on the fence forming part of the device, incident to the 95 pressure of water thereagainst, will be directed against the abutments instead of against the support 8, thereby greatly reinforcing the parts of the fence structure.

By anchoring the support 8 by means of the bolts 14 and having said bolts adjustable with respect to the anchoring plates 10, the fence structure, while made in a prescribed length, may be readily fitted to abutments of different lengths and heights, so that any inaccuracies in the dimensions of the abutments when built will be compensated for 100 110

without necessitating the changing of the length of the fence forming part of the device. In addition to the adjustment of the clamping bolts 14 with respect to the clamping plates 10, one or more blocks 19 may be introduced below the support 8 for elevating said support in the event the abutments are too short to accommodate the fence structure, or for elevating support 8, and that 10 end of fence forming bars 9 attached thereto, for any desired purpose, this feature being shown in Figure 4 of the drawing.

As the greater volume of water is at the center of the stream, the support 8 is preferably reinforced longitudinally to prevent the same from bending under excess strain and to properly accomplish this result, a pair of rods 20 are provided, each rod having its outer end entered through an opening 21 in the web portion of the support 8, and provided with an extension 22, which lies substantially parallel with the face of the web when the rods are in proper anchored position. The meeting 25 ends of the rods 20 are threaded to receive a turn buckle 23 by means of which the rods may be drawn taut, each rod passing over a truss block 24 so that the tension of the rods will be directed principally at the ends of 30 the support 8, and consequently greatly reinforcing the support at its longitudinal center or at a point receiving the greatest amount of strain. The anchor plates 10, as shown in the drawings, are built of two parts 35 alleling sections spaced apart which are connected together at their ends by straps, but it will be clearly understood that said plates may be cast solid with the exception of the elongated slot 13, and in order to permit the bolts 14 to be adjusted in the slots 13, the upper faces of the ledges 7 are provided with channels 25 in which the heads of the bolts 14 project.

In Figure 5 of the drawings a slightly modified means is shown for attaching the bars 9 to the support 8, and in this instance an insert block 26 is introduced between the upper face of the support 8 and the ends of the bars 9 and a bolt 27 is extended downwardly through each of the blocks 26 and through the support 8 and bar 9 co-operating therewith. The object in elevating the ends of the bars 9 a distance above the support 8 is to permit trash or the like to pass over the upper ends of the bars 9 without engaging and lodging against the support 8. This feature, however, is not essential except in streams which carry an unusual amount of trash.

In the event the stream is of considerable width it is preferable to support the bar 8 at a point or points between the abutments, and to this end a chair 28 is provided which is to be slipped over the end of the support 65 8 and properly positioned in the length

thereof, each chair having a recess 29 transversely thereof for the reception of the base of the support 8, and also having an extension 30 to which is attached a sleeve 31 and into the lower end of said sleeve is introduced a metallic post 32 to the lower end of which is attached a base plate 33 for supporting the post 32. The sleeve 31 is slidably mounted upon the post 32 so that the chair and sleeve may be adjusted to various heights, and in order to hold the sleeve in adjusted position, a collar 34 surrounding the post 32 is moved upwardly on the post until it engages the lower end of the sleeve 31 and by then clamping the collar onto the post the sleeve will be held in fixed position until such time as the collar 34 is again loosened. It will also be understood that additional abutment may be provided for supporting the member 8 between its ends if desired. 70 75 80 85

As best shown in Figure 2 of the drawings, the bars 9 are set at an angle, the lower ends of the bars being upstream and below the surface of the water under normal conditions, or may be rested directly on the bed of the stream, and by positioning the bars 9 in this manner any refuse carried by the water, especially during floods, will readily ride up the inclined bars and discharge over the support at the down stream end of the bars. 90 95

It will likewise be seen that by extending the cross bar 18 over the ends of the abutments 1 and 2 the major portion of the strain is directed against the abutments, consequently the device will be practically indestructible and will withstand the most severe flood waters as the tendency of trash and the like to permanently lodge on parts of the fence structure is practically eliminated. 100 105 110

Having thus fully described my said invention, what I claim as new and desire to secure by Letters Patent, is:

1. In a water bed fence construction, a plurality of inclined bars having their lower ends extending upstream, abutments at each side of the group of bars, plates resting upon and secured to parts of said abutments for receiving the ends of said support, a support for the opposite ends of said bars associated with said plates, and means for adjusting said support vertically for controlling the angle of said bar. 115 120

2. In a water bed fence, a pair of abutments, a plurality of inclined bars between said abutments, a support for the higher ends of said bars, means for adjusting said support vertically and laterally, and means connecting the lower ends of said bars and extending into engagement with the ends of said abutments. 125

3. In a water bed fence structure, a plurality of inclined spaced bars, means for 130

connecting the lower ends of said bars, a transversely extending support attached to the elevated ends of said bars, and means for re-inforcing and bracing said support 5 at its point of greatest strain.

4. In a water bed fence, a pair of spaced abutments, an anchoring plate secured adjacent one end of each abutment, a support extending crosswise of the abutment and having 10 its ends resting on said plates, means for adjustably securing the support to said plates, a plurality of bars having one of their ends connected with said support, and a cross bar to which the opposite ends of 15 said bars are connected.

5. In a water bed fence construction, a pair of spaced abutments having ledges adjacent one end thereof, an anchoring plate fixed on each ledge, said plates having elongated slots, a support extending from one abutment to the other and having its ends projecting over said plates, means for vertically and laterally adjusting said support on 20 said plates, and a plurality of bars connected with said support.

6. In a water bed fence, abutments, a support extending from one abutment to an-

other crosswise of a stream, a plurality of fence forming bars, means for attaching one end of the bars to said support, and insert 30 blocks for supporting the ends of the bars co-operating with said support a distance above the support whereby trash, or the like, will pass over the support without catching thereon.

7. In a water bed fence, abutments, a support having its ends resting on said abutments, a plurality of bars connected with said support, reinforcing members having one end in engagement with the ground and 40 their opposite ends in engagement with the under face of said support, and means for adjusting said reinforcing members vertically for sustaining the weight of said support at points between its ends.

In witness whereof, I have hereunto set my hand and seal at Indianapolis, Indiana, this 23rd day of September, A. D. nineteen hundred and twenty-one.

RUBY P. STINE. [L.s.]
